HOLDER FOR DENTAL CLEANSING NOZZLES OR THE LIKE

James Herbert Sullivan, Lake Forest, Ill., assignor to Miles Laboratories, Inc., Elkhart, Ind., a corporation of Indiana

Filed Aug. 31, 1967, Ser. No. 8,445

Term of patent 14 years

(Cl. D24—1)

The figure is a perspective view of a holder for dental cleansing nozzles or the like showing my new design, the opposite side being a mirror image of the side shown.

The broken lines are shown for illustrative purposes only.

I claim:

The ornamental design for a holder for dental cleansing nozzles or the like, substantially as shown and described.
